LAY-FIGURE FOR GARMENT DISPLAYS

Bernhard Linz, Berlin, Germany

Application September 26, 1933, Serial No. 690,981
In Germany August 3, 1933

7 Claims. (Cl. 223—68)

This invention relates to a construction of lay-figure for the display of garments, cloth and the like.

It is an object of the invention to provide a lay-figure which may be employed universally for the display of ladies', men's and children's garments, whether in a single piece or comprising several pieces.

A further object of the invention is to provide a lay-figure in which the various parts may be adjusted and formed into various shapes and configurations to produce any desired effect in the display of the garment.

A still further object of the invention is to provide a lay-figure adapted for the display of different sizes of garment.

Still another object of the invention is to provide a lay-figure which may be employed for the display of head gear, that is hats or caps and the like, simultaneously with garments.

Still another object of the invention is to provide means whereby garments may be held in position on a lay figure without causing damage to such garments.

Further objects and advantages of the invention will be apparent from the description as it proceeds.

The lay-figure according to the invention may be built up of body parts of substantially flat, sheet or plate material to which are appended wire-like, rigid or flexible members forming the limbs of the lay-figure and may further comprise a shoulder plate or shoulder plates upon which the garment is hung. The shoulder plate may be surmounted by a device for the display of millinery, and this may comprise a plurality of deformable linear elements adapted to be shaped to a form suitable for the display of a given article thereon.

In order that the figure may be adapted for sitting or reclining postures it may be supported on an upright which swivels about a point close to the base. The upright may also be divided so that a lower section may be removed and the device thus enabled to take up a sitting posture on a chair or the like.

The various parts of the figure may be removed or adjusted to suit the particular effect it is required to produce.

In order that the invention may be clearly understood, an example thereof will now be described with reference to the accompanying drawings in which:

Fig. 1 is a front view of the lay-figure for standing or upright exhibits.

Fig. 2 is a side view of the same lay-figure.

Fig. 3 is a plan view of the pedestal of the lay-figure.

Fig. 4 is a rear view of the hip plate.

Fig. 5 is a detail.

Fig. 6 is a side view of the lay-figure adjusted for reclining exhibits.

Fig. 7 is a side view of the figure for sitting exhibits.

Fig. 8 is a detail.

Figs. 9, 10, and 11, are front views, each showing different positions which may be given to the arms.

Referring first to Fig. 1, 30 denotes the pedestal of the figure. This pedestal may have any desired form and may be made in one piece or built up from several pieces. The support 31 is screw threaded into the pedestal 30. The connection of the support to the pedestal may also be made in other ways, preferably however so that the connection is easily demountable. Arranged telescopically within the support 31 (which, for the purpose of rigidity, is arranged as near as possible to the edge of the pedestal 30) is a rod 32 which may be drawn out from 31 and fixed at any desired height by means of a set screw 33. On the part 32' of the support 31 there is provided a bracket 34 which may be constructed so as to be detachable; on the bracket 34 is provided a back plate 35 which extends parallel to the support 31. The back plate 35 carries the body structure 38 comprising a plurality of parts of substantially flat, sheet or plate material which are relatively adjustable thereon as hereinafter described. The rod 32 carries at the top a forwardly adjustable arm 32'' to which a curved member 36 is fixed. Around the hip plate 38, which may be entirely or partly covered with cloth or other material, a rubber band or the like 48 is stretched. The adjustable arm 32'' may also be provided with a price ticket device 15. The price ticket may be variable in position.

The rod 31 is subdivided into the rods 31' and 32'. The rod 31' is preferably provided, near the pedestal 30, with a swivel joint 37. As illustrated, this latter may consist of a slot and pin connection for adjusting the rod 31 in one plane, but may also consist of a ball-and-socket joint with one or more preferably hand-operated set screws for the purpose of adjustment in all planes.

As will be better seen in Fig. 2, there is arranged on the support 31 a strut 16 which comprises a tube 17 and a rod 18. The tube 17 is provided with clips 19 which are easily releasable.

The strut 16 can be shortened by displacing the rod 18 inwardly.

The body structure 38 with or without an adjustable bust extension 39, 40 consists, as can be seen from Fig. 4, of two parts 41 and 42. Strips 14 provided with a dove-tailed groove are attached to both parts. The correspondingly shaped strips 20 provided on the rod 35 engage in the grooves. The body parts 41 and 42 are fastened in position by means of knurled screws 21. At the top of the body parts 41 and 42, shapings 22 are provided which can be adjusted forwards and backwards by means of knurled screws 23.

On the rod 32 there is fixed a square sleeve 6, 15 in which a square rod 5 is arranged so as to be adjustable and fixable. The rod 5 carries a square sleeve 8 in which the square rod 24 is arranged so as to be displaceable and fixable. On the rod 24 there is fixed the curved transverse rod 36. 20 On the latter are provided the shoulder plates 10 and 11. Underneath the shoulder plates 10 and 11 is arranged a plate 21 which conforms to the curved shoulder member 36 and serves for covering the seams and also the number markings etc. of the wearing apparel, so that a clean and decorative cut of the neck is obtained. A wire 43 simulating an arm is provided insertable by means of a pin 12 in a sleeve 12' at one end of the rod 36. This consists, as can be seen from 25 Fig. 5, of a core of soft material, such as copper, around which is wound brass or other wire. The wire is rigidly connected to the core at its lower and upper ends, so that the wire 43 can be bent into any desired position and bent back again. 30 In the same way, a wire 44 is connected to the rod 36 at the other end. The wire 44 may be constructed like 43 or it may be rigid. Around the wire 44 is wound a further steel wire 44' which may reproduce the outline of an arm. The member 45 is constructed in like manner to the member 44 to simulate a leg, whilst the member 46 corresponds in construction to that of the arm 43. The members 45 and 46 may be detachable. 35 On the adjustable arm 32'' a ball 3 is detachably mounted on a plug 4 in a sleeve 5. The ball 3 carries a number of wires 2 which are constructed in a similar manner to the wire 43.

Fig. 6 shows the lay-figure adjusted for reclining displays and is provided with the same reference characters as the figures hereinbefore described. As can be seen, the swivel joint 37 is bent downwards and the strut 16 on the rod 31 moved to a greater distance from the pedestal 30. This can easily be effected by the clip-shaped fixture 19.

In Fig. 7, which illustrates the figure adapted for sitting displays, the lay-figure is arranged on a chair 25. As can easily be seen, the part 31' of the support 31 has been removed.

Fig. 8 shows a ball-and-socket joint which may be employed at the bottom of the rod 32.

The display is arranged, for instance, in the manner hereinafter described.

If a mantle or fur coat is to be exhibited, it is placed with its collar around the transverse arm 36. The arm portions 44 and 43 are passed through the sleeves of the cloak and bent into the shape in which it is desired to represent the arms. The body structure 38 is shifted to that distance from the transverse arm 36 which is suitable for the natural representation of the shape of the body. The rear part of the fur coat is introduced into the intermediate space between the plate 35 and the support 31. The other parts

of the lay-figure are generally not employed in the case of cloaks or mantles.

In a one-piece dress with long sleeves, the display is arranged initially in the same manner; however, the clamping devices 49 are employed in this case, in order to produce and retain the correct contour from the waist downwards. The hem of the skirt can be firmly gripped at the lower ends of the leg portions 45, 46. The members 45, 46 can be deformed into any desired configuration to simulate true-to-life shapes of the lower part of the garment.

In the case of two-piece garments, the skirt is first of all fixed upon the structure 38 by means of the rubber band 48 and, as has already been described, is given the desired outline by means of the deformable members 45, 46. The blouse, pullover or other garment completing the two-piece ensemble is placed over the arm 36, and, if provided with sleeves, over the wire arms 44, 20 43, and is fixed by means of the clamping device 49. A jacket is dealt with in the same manner as a blouse.

In this manner, it is possible by means of a single device or a number of similar devices, to 25 display plastically the most varied garments of any size and shape. The use of pins or other devices which may damage the materials is strictly avoided.

However, sitting, standing and reclining displays are all possible with one and the same lay-figure. In addition, by the lateral adjustment of the body parts 41, 42, the display of wearing apparel of any desired widths can be effected. The band 48, preferably of rubber, serves for fixing the lower part of a garment consisting of two or more pieces. Owing to the adjustability of the body structure, the band is preferably provided with a buckle 48'. Behind the body structure 38 there are provided springs 50 with rods 49 fixed thereto. The rods, which are preferably round, and also the springs may be covered with cloth or other padding material for the protection of the displayed garments.

These have the function of firmly clamping the garment arranged on the hip plate, so that no pins are required. The forward adjustability of the arm 32'' has for its main object to produce a better shape of garments provided with furs. The adjustment provides a greater space behind the transverse arm 36 for the various sizes of fur collars thus preventing damage to them.

The many adjustments, i. e., the adjustment of the body structure 38 upon the rod 32 by means of the bracket 34, the adjustment of the sides 41, 42 towards and away from one another, the backward and forward adjustment of the arm 32'', and the bust portions 22, enable all types of garments to be displayed.

By rotating the support 31, illustrated in Fig. 6, by 90°, the display of garments in side view can also be effected.

In the lay-figure as shown in Fig. 7, the lower part of the garment is placed over the front edge of the chair so that the garment of a sitting person is imitated. In order to imitate a person sitting on the ground, a ball-and-socket joint such as that shown in Fig. 8, may be provided between the rod 32' and the pedestal 30, it then being possible also to imitate a person whose legs are stretched sideways.

The wires 2 may be given any desired shape, so that a large number of supporting points are provided for the head covering. Any deformation of the hats which otherwise occurs particularly

in the case of hats of delicate material is thus avoided. A coiffure can also be simultaneously displayed.

5 The side edges of the body parts 41, 42 may be of any desired shape, so that ladies' and also gentlemen's garments can be displayed.

For gentlemen's garments, the body parts are preferably made of the shape shown in dotted lines (47).

10 Finally, it is preferable to provide several pairs of arms 43, 44 for use alternatively with each lay-figure. For instance, three pairs of arms, may be provided which are curved in two planes, as shown in Figs. 9 to 11. They present a curvature 15 as seen from the front and a further curvature as seen from the side. In this manner, the lay-figure can be used in many different ways and, above all, small firms which do not have trained dressers at their disposal, are enabled, by interchanging the three pairs of arms provided, to obtain harmonizing and anatomically correct effects, which enhance the sale value of the garments displayed on the lay-figure.

It is apparent that the limb members 43, 44, 25 45 and 46 may be constructed of wire, rod or tube-like material and the invention is not confined to the use of the "stay-put" flexible material, the construction of which is described with reference to Fig. 5. In the appended claims therefore the term "wire-like" is intended to refer to material 30 of rod, wire or tube form having the essential characteristic that it is slender and may be given the natural pose of a limb.

I claim:

35 1. Lay-figure for garment displays comprising an upright, a bracket supporting a back plate mounted upon said upright, complementary body plates adjustably mounted on said back plate, means on said back plate comprising a spring clip 40 for retaining a garment in position on said body plates, a shoulder plate mounted on said upright, arm members depending from said shoulder plate and leg members depending from said body plates.

2. Lay-figure for garment displays comprising 45 an upright, a bracket supporting a back plate movably arranged on said upright, means for retaining said bracket at any desired position on said upright, a plurality of body parts of substantially flat, sheet or plate material movably arranged on said back plate and means for retaining said body parts in any desired relation to form a substantially flat trunk structure of the required dimensions, a shoulder member also mounted on said upright and means for retaining said shoulder member in any desired position relative to said body parts to complete a torso of the required dimensions, arm members of wire-like material depending from said shoulder member and leg members of wire-like material depending from 50 said trunk structure.

3. Lay-figure for garment displays comprising 55 an upright, a bracket supporting a back plate movably arranged on said upright, means for retaining said bracket at any desired position on said upright, a plurality of body parts of substantially flat sheet or plate material movably arranged on said back plate and means for retaining said body parts in any desired relation to form a substantially flat trunk structure of the required 60 dimensions, a shoulder member also

mounted on said upright and means for retaining said shoulder member in any desired position relative to said body parts to complete a torso of the required dimensions, arm members of stay-put flexible wire-like material depending from 5 said shoulder member and leg members of stay-put flexible wire-like material depending from said trunk structure.

4. Lay-figure for garment displays comprising 10 an upright, a bracket supporting a back plate movably arranged on said upright, means for retaining said bracket in any desired position on said upright, supporting members on said back plate, a plurality of plates provided with guides 15 and displaceably supported thereby upon said supporting members, means for retaining said body plates in any adjusted position on said back plate to form a substantially flat body structure of the required dimensions, a shoulder member, a rod supported horizontally on said upright and displaceable horizontally relative thereto supporting 20 said shoulder member and means for retaining said rod with said shoulder member in any adjusted position, to complete with said body structure a torso structure, arm members of wire-like 25 material depending from said shoulder member, and leg members of wire-like material depending from said body structure.

5. Lay-figure for garment displays comprising 30 an upright, a plurality of body parts of substantially flat, sheet or plate material movably supported on said upright, means for retaining said body parts in any desired relative positions to form a substantially flat trunk structure of the required dimensions, a shoulder member movably 35 arranged on said upright and means for retaining said shoulder member in any desired position relative to said body parts to complete with said body parts a substantially flat torso structure, and a millinery display device surmounting said 40 shoulder member, said millinery display device comprising a plurality of stay-put flexible members bendable to conform to the interior contour of the head wear to be displayed thereon.

6. Lay-figure for garment displays comprising 45 a pedestal, an upright supported on said pedestal, said upright being articulated near its lower end, a strut supporting said upright above the point of articulation, a bracket supporting a back-plate movably arranged on said upright, a set screw for locking 50 said bracket in any desired position on said upright, a pair of substantially flat body parts mounted on horizontal guides, on said back plate, means for retaining said body parts in any desired horizontal adjustment on said back plate 55 to form a substantially flat body structure of the required dimensions, shaping members mounted on said body parts, a shoulder member movably arranged on said upright and means for retaining said shoulder member in any desired position relative to 60 said body parts to form therewith a torso structure of the required dimensions, a millinery display device surmounting said shoulder member and means for retaining a garment in position on said figure.

7. Lay-figure as claimed in claim 6, wherein 65 a spring clip is provided on said back plate to retain a garment in position thereon.
